FIRE DETECTION ALARM COVER

David M. Sanger, Livingston, N.J., and Thurston H. Toeppen, Poughkeepsie, N.Y., assignors to General Signal Corporation, Rochester, N.Y.

Filed May 5, 1971, Ser. No. 140,652

Term of patent 14 years

Int. Cl. D29—01

U.S. Cl. D72—1

FIG. 1

FIG. 2

FIG. 3

FIG. 1 is a top plan view of a fire detection alarm cover showing my new design;

FIG. 2 is a side elevational view thereof;

FIG. 3 is a cross-sectional view taken on line 3—3 of FIG. 1, the cover being fragmentarily shown for convenience of illustration.

We claim:

The ornamental design for a fire detection alarm cover, as shown and described.
